UNITED STATES PATENT OFFICE.

EMIL ALTMAN, OF BROOKLYN, NEW YORK.

GARMENT.

1,114,955.

Specification of Letters Patent.

Patented Oct. 27, 1914.

Application filed April 6, 1911. Serial No. 619,224.

To all whom it may concern:

Be it known that I, EMIL ALTMAN, a citizen of the United States, and resident of the borough of Brooklyn, county of Kings, and State of New York, have invented certain new and useful Improvements in Garments, of which the following is a specification.

My invention relates to garments and more particularly to undergarments and has for 10 its object to provide such garments with a device or devices which, when in position on the garment, will provide a means to which various attachments such as garters, elastic straps for contracting or otherwise adjusting 15 the garment and the like, may be easily, quickly and securely fastened or coupled, and from which said attachments may be readily released or disconnected.

A further object of my improvement is to 20 so construct the device that it will take up all strains exerted by the particular attachment in use and thus prevent tearing of the garment and will also preserve the smoothness of the garment and prevent the attachment 25 from forming creases or uncomfortable protuberances.

My invention will be fully described hereinafter and the features of novelty thereof will be pointed out in the appended claims.

Reference is to be had to the accompanying drawings, in which—

Figure 1 is a side elevation of an undergarment; Fig. 2 is a rear elevation thereof; Fig. 3 is an enlarged detail view of my improvement made as a separate element and shown detached from the garment; Fig. 4 is a cross section thereof on the line 4—4 of Fig. 1; Fig. 5 is a section on the line 5—5 of Fig. 2 illustrating another application of 40 my invention; and Fig. 6 is a detail view of a filler which is used in connection with my invention, and Figs. 7 and 8 are face and side elevations respectively of one form of attachment.

For the purposes of clearly describing and illustrating its operation I have shown my invention in the drawings as applied to knee drawers, although it is to be distinctly understood that this is only a specific illustration of one of the many uses to which my improvement may be put.

The improvement itself, when made as a separate element, as shown best in Figs. 3 and 4, is in the nature of a projection applied to the garment, and in the illustration comprises a strip of fabric which is doubled

upon itself and sewed together as indicated at *a* to form a fold or other thickened portion. The sewing or row of stitches *a* is preferably located parallel with and a short distance from the double edge so as to form a tubular portion *b* and two adjacent straight portions or flaps *c*. In the preferred form of my improvement a cord or other filler *d* is introduced into the tubular portion *b* so as to form a substantially solid yet yielding projection extending lengthwise of the device. The cord or filler *d* is preferably made with spaced relatively large oval portions *d'* connected together by means of relatively small or thin connecting portions *d''* to form an undulating structure, as clearly shown in Fig. 6.

The device as illustrated and described is applied to the garment by stitching along 75 the free edges of the straight portions or flaps *c* as indicated at *e* and along the two opposite ends thereof as shown at *e'*, the stitches *e* extending only up to the stitches *a* and in any case preferably never beyond the 80 tubular portion *b*. With this construction the entire tubular portion *b* is free from the garment, as clearly shown in Fig. 4 and forms what might be termed a coupling member. The location of the device on the 85 garment will depend entirely on the use for which it is intended. If it is intended to afford a means of attachment for a garter, the said device will be secured to the leg of an underdrawer in proper position to suit 90 individual desires. In this instance the clasp *f* of the garter *f'* is slipped over the projection composed of the tubular portion *b* and a slight pull exerted thereon which will cause said clasp *f* to move downwardly relatively to said portion *b* and one of the oval portions *d'* to work up into the reduced slot *f''* of said clasp as shown in Fig. 1 and Fig. 7. In this condition the clasp *f* is firmly held against farther downward movement 100 by the adjacent oval portion *d'* and is also frictionally held against accidental dislocation in an upward direction owing to its firm grip on the tubular portion *b* and the pull of the clasp will be lengthwise of the said portion *b*. If the filler or cord *d* is omitted, the tubular portion *b* will simply be gripped in the reduced slot of the clasp *f* in the same manner as just described and the clasp will thus be firmly held in proper position 110 against movement relatively to the said tubular portion. The attachment of the gar-

ter in the manner described may take place at any desired point along the coupling or tubular portion *b* so that the depending length of garter may be easily regulated.

As shown best in Fig. 5, the garment itself may be folded or otherwise manipulated to produce a projection, for instance, by being formed with a tubular portion *g* through the medium of stitching *g'* and a filler or cord *d³* similar to the cord *d* inserted in said tubular portion *g* if desired. In the specific illustration shown this form of my invention has been applied to the rear of a garment at spaced intervals to form a means on which a contracting or adjusting device may be secured for adjusting the waist of the garment. This device may be of any suitable kind and in the illustration comprises two clasps *f²* similar to the clasp *f* and connected by preferably elastic band *f³*. If desired this band *f³* may be a simple connecting strip of non-elastic material. The operation and mode of attachment is the same as hereinbefore described with respect to the garter the pull of the clasp being also lengthwise of the projection and as the device may be attached at any point along the tubular or other projecting portions *g* a wide range of adjustability of the waist of the garment is secured and the usual strap and buckle or tie strings or laces are done away with.

As another instance of the uses to which my invention may be put, the garment illustrated may be provided at the front or rear or at both places adjacent to the waist line with projections as for instance vertically extending devices of either of the forms described and another garment such as an undershirt may be similarly provided with similar devices. The devices on each garment may then be coupled or connected together by a device similar to that comprising the elements *f²* so that both garments will then become united either at the front or rear or at both points. In the case of undergarments all the advantages of a union garment are thus secured without sacrificing any of the advantages of the two piece separate garments and a relative separation movement between said garments is prevented. This connection between the two garments is readily adjusted by simply connecting the clasps such as *f²* at different points along the projections or tubular portions such as *b* or *g*. An outer shirt may be similarly provided with a similar device and similarly connected with another garment to maintain said outer shirt in proper and comfortable position. In all its applications the device in whatever form it is used, preserves the smoothness of the garment and prevents the particular attachment from forming creases or gathers and uncomfortable protuberances particularly on

the inner surface and furthermore takes up all strains exerted by the attachment, thus preventing tearing or other manipulating of the garment.

While I have illustrated all forms of my improvement as applied to knee drawers, it is to be understood that it is equally applicable to full length drawers and is also capable of use in many other ways which will readily suggest themselves and need not be individually described or shown. It will be seen from the description that my invention provides a ready securing means or coupling medium on which various attachments may be secured and is easily and quickly embodied in finished garments of almost any description. It will be further understood that while I prefer to use the filler or cord such as *d* the same may be omitted and the material simply shaped to form projecting portions of any suitable kind such as *b* or *g* which portions in this case may be tubular or otherwise as desired. Furthermore instead of the cord illustrated, an ordinary cord of even diameter or some other material may be substituted as a filler. Whatever may be the particular construction employed for the securing means, the ridge is generally placed on some part of the garment between seams and this ridge is also formed of laterally compressible material of limited length by which is meant that the ridge is shorter than the length of the garment at the point where the ridge is applied.

In Figs 7 and 8 I have illustrated in detail the particular construction of one form of improved attachment devised by me for use in connection with the structure so far described or adapted for all uses where a quick and positive connection with a garment is desired. The clasp *f* is preferably curved in a direction transverse to its length and is provided with a reduced slot *f⁴* of such a width as to frictionally engage the garment or the particular improvement described hereinbefore and thus securely maintain the clasp *f* against accidental displacement. The curved form of said clasp makes it easy to connect said clasp with the garment itself or the particular improvement described above without necessity for careful manipulation. That is the portion of the garment itself or my particular improvement as the case may be will readily force itself up into the slot *f⁴* as a pull is exerted on the clasp *f*. This form of clasp may also be incorporated in the attachment composed of the parts *f²* and *f³* and in this case operates the same way and has the same advantages as when employed in connection with a garter.

Various changes in the specific forms illustrated and described may be made within the scope of the claims without departing from the spirit of my invention.

I claim—

1. A garment comprising means for detachably receiving the fastening device, said means consisting of laterally compressible material of limited length permanently attached to the said garment at one of its unseamed parts whereby a projection is formed above the normal surface of the garment, adapted to be wedged or compressed within a narrow slotted fastening means and to hold the same along the line of tension exercised by said fastening means.
2. In a garment, a projecting fold of material, means adapted to render the free edge of said fold alternately thick and thin, said thin portions being adapted to be

wedged into an attaching device, and said thick portions serving to prevent disconnection of the fastening device in one direction.

3. In an undergarment, a flap having its one edge secured thereto and its opposite edge free from said garment, a tubular projection extending lengthwise of the free edge of said flaps and a filler located in said tubular projection.

In testimony whereof I have hereunto set my hand in the presence of two subscribing witnesses.

EMIL ALTMAN.
